(No Model.)

M. D. PETERSON.
COMBINATION WHIP SOCKET AND REIN HOLDER.

No. 586,744.

Patented July 20, 1897.

UNITED STATES PATENT OFFICE.

MARCUS D. PETERSON, OF LONG LAKE, MINNESOTA.

COMBINATION WHIP-SOCKET AND REIN-HOLDER.

SPECIFICATION forming part of Letters Patent No. 586,744, dated July 20, 1897.

Application filed January 23, 1897. Serial No. 620,362. (No model.)

To all whom it may concern:

Be it known that I, MARCUS D. PETERSON, residing at Long Lake, in the county of Hennepin and State of Minnesota, have invented 5 a new and useful Combination Whip-Socket and Rein-Holder, of which the following is a specification.

This invention is a combination whip-socket and rein-holder, the object being to provide a 10 device of the kind described which shall be constructed of a single piece of wire and which can be quickly and easily fitted upon a vehicle of any description.

Another object is to construct a combination whip-socket and rein-holder in such a 15 manner that it will be securely held upon the dashboard and prevented from rattling.

Another object is to construct a combination whip-socket and rein-holder which will 20 securely hold both at the same time or either at one time.

With these various objects in view my invention consists, essentially, of a socket composed of four members, a clip attached to the 25 forward side of the socket for attaching the same to the dashboard, and a clip connected to the rear side of the socket for the purpose of receiving the reins.

The invention consists also in certain de- 30 tails of construction and novelties of combination, all of which will be fully described hereinafter, and pointed out in the claims.

In the drawings forming a part of this specification, Figure 1 is a view showing the practical application of my invention. Fig. 2 is 35 a detail perspective view of the combination whip-socket and rein-holder. Fig. 3 is a top plan view. Fig. 4 is a sectional view taken on the line 4-4 of Fig. 2.

In carrying out my invention I employ a 40 single piece of stout wire, which is bent centrally upon itself to provide a depending clip A, which is adapted to fit over the top of the dashboard. The wire is then bent at B and 45 carried downwardly at C to provide two members of the socket. After forming the side members of the socket the wire is bent across at right angles, as shown at D, in order to provide the bottom members of the socket

and is then bent upwardly to provide the 50 rear side members E of the socket. The wire is then again bent at F and carried downwardly, as shown at G, bent upwardly at H to provide the rein-clip, outwardly at H' to provide the flaring entrance to the rein-clip, 55 and the ends of the wire are then united, thereby forming the combination whip-socket and rein-holder of one piece.

The depending clip formed at the upper end of the socket is adapted to fit over the 60 top of the dashboard and the upwardly-projecting clip formed at the lower end of the socket is adapted to receive and hold the reins.

The four upright members of the socket 65 securely hold the whip in place and the bottom members D prevent the whip passing through the socket, as most clearly shown in Figs. 3 and 4.

It will thus be seen that I provide an ex- 70 ceedingly cheap, simple, and efficient construction of combination whip-socket and rein-holder, which will thoroughly carry out all of the objects for which it is intended.

Having thus described my invention, what 75 I claim as new, and desire to secure by Letters Patent, is—

1. A combination whip-socket and rein- 80 holder, formed of a single piece of wire and comprising the clip A, the bends B, the mem- bers C, D and E, providing the socket, the bends F, members G and H, all arranged and adapted to operate, substantially as shown and described.

2. The herein-described rein holder or sup- 85 porter comprising a socket having the side members substantially as described, the bottom bars, a depending clip or clamp adapted to engage the dashboard, an upwardly-ex- 90 tendsing clip constructed as described for the reception of the reins, the upwardly-extending portions of said clip being flared or curved outwardly for the purpose set forth.

MARCUS D. PETERSON.
